UNITED STATES PATENT OFFICE.

RALPH CROMPTON, OF ELTON, NEAR BURY, COUNTY OF LANCASTER,
ENGLAND.

APPARATUS FOR DYEING AND DRYING TISSUE AND OTHER PAPER.

SPECIFICATION forming part of Letters Patent No. 397,069, dated January 29, 1889.

Application filed March 7, 1888. Serial No. 266,479. (No model.)

To all whom it may concern:

Be it known that I, RALPH CROMPTON, a subject of the Queen of Great Britain, and a resident of Elton, near Bury, in the county of 5 Lancaster, England, manufacturer, have invented certain new and useful Improvements in Apparatus for Dyeing Tissue and other Paper, of which the following is a specification, reference being had to the accompanying drawings.

My invention relates to an improved apparatus for treating tissue and other paper in continuous rolls, after manufacture, with various solutions, chemicals, coloring-matter or dyes, and then drying the same. The invention 15 is applicable to the manufacture of tracing-paper, water-proof paper, check-paper, and almost any kind that requires chemical treatment after manufacture.

20 The invention may also be applied to the paper-making machine, in which case the coloring or mordanting rolls may be placed in a suitable position between the drying-cylinders or between two sets of drying-cylinders, 25 or replacing the so-called "intermediate calender," the paper being dried, or nearly so, by the first set of cylinders, and, after being treated, finally dried by the second set of cylinders.

30 Hitherto it has only been possible to treat tissues and thin papers in the web with solutions at considerable expense, owing to the great waste of materials used through the paper breaking so frequently and other causes.

35 By my invention it is possible to impregnate a roll of tissue-paper with a chemical solution or dye and dry the same, (without injury to the colors,) and without any appreciable waste of paper, solution, or dye. Brighter 40 and darker shades may be produced by my apparatus than by any other.

According to this invention, I pass the tissue or other paper in a vertical direction, or 45 nearly so, down between two pressing-rolls covered with felt, cloth, or other suitable porous substance, and suitably supplied with dye and serving to more or less impregnate the paper with the coloring-matter, while removing the surplus of same. For some kinds

50 of paper the rolls may be covered with rub-

ber or other similar substance and used without the felt covering, or one metal roll and one rubber-covered roll may be used together. It will thus be understood that the dyeing, 55 pressing, and removing the surplus solution are performed in one operation and by one pair of rolls. I may by similar means apply a mordant to the tissue or other paper before or after applying the die, and by preference in the same machine.

60 By the aforesaid arrangement I avoid the need for special means of support to the wet tissue-paper. The paper thus far treated is then passed unsupported through a drying apparatus arranged close to the pressing-rolls 65 or (in case of mordanting as well as dyeing) the last pair of pressing-rolls.

70 Figure 1 of the accompanying drawings is a part sectional elevation of one form of apparatus for mordanting or dyeing tissue and other paper. Fig. 2 is a similar view of the principal parts of another form of the apparatus; and Figs. 3^A, 3^B, 3^C, and 3^D form a similar view of a complete apparatus for mordanting, dyeing, and drying tissue and other 75 paper. The figure is shown in continuation on Sheets 2, 3, 4, and 5, one part being shown on each sheet, beginning on the left and continuing on toward the right.

70 In the form of apparatus shown in Fig. 1 I employ two metal or wood rollers, C C, covered with felt, cloth, or other suitable absorbent material, or two rubber-covered rollers, or one metal and one rubber-covered roller. These rollers are placed at or about the same 80 level, or one raised slightly above the other. The rolls are mounted in suitable frames with screw or lever pressure arrangement at each end, and are caused to revolve inward. The solution for mordanting or chemically treating or the dye for coloring is run between the nip or point of contact of the rollers C C from a tank, F, by the pipe G, terminating in the 85 perforated pipe G', or other suitable appliance placed above, or it may, as shown in the 90 part elevation, Fig. 2, be supplied to the felt-covered rollers C C by means of feed-rollers N N', revolving in dye-troughs O O', or by any other suitable methods.

100 The paper, A, to be treated or dyed is drawn

off from a continuous roll, and by preference passed over a guide-roll, B, placed above the felt-covered rollers C C. It then enters between the nip of the pressure-rollers C C. By 5 this means the paper passes through a small quantity of solution lying just above the nip of the pressure-rollers, and immediately afterward receives the pressure of the rollers and becomes impregnated. I thus do away with 10 the necessity for endless supporting-bands for the wet tissue-paper. The surplus solution or dye runs off at each end of the pressure-rolls and is caught by a receiver or trough, H, placed underneath, from which it flows 15 into the main tank, so that it may be used over again. The bulk of the solution is in Fig. 1 placed in a double-cased tank, D, which may be steam-heated or not below the pressure-rollers, and is pumped up, for instance, by a pump, E, and pipe E' into a 20 small box, F, above, from which it is supplied to the rollers, the box having an overflow-pipe, I, into the main tank D, so as to keep up a regular pressure and make the action continual.

25 The solution need not be run onto the pressure-rollers in such quantities as to form a bath above the nip, but just sufficient may be used to moisten the felt covers on the rollers, the result obtained being almost the same. Felt-covered doctors P P', as shown in Fig. 2, or other suitable means, may be applied to the pressure-rolls to keep back the surplus liquid.

30 35 The pressure on the ends of the rollers may be so regulated as not to press the dye right through the paper, but may be worked to color it on the surface only or to any desired degree of penetration.

40 45 In coloring I sometimes employ two pairs of felt, rubber, or other covered rollers, as shown in Figs. 3^A, 3^B, 3^C, and 3^D, which form a side view of a complete mordanting, dyeing, and drying apparatus, the one pair Q Q to impart the mordant and the other pair, C C, the dye to the paper. Sometimes I dry the paper after mordanting and before coloring, and I prefer to do this by a steam-heated cylinder, L', placed between or above the two pairs 50 of pressing-rolls and provided with the usual endless felt, M'. After the paper has passed through the nip of the pressure-rollers it is taken off at one side and conducted unsupported direct to a drying appliance consisting, by preference, of a system of air-drums (with interior fans) and steam-heated drying-cylinders, (fitted in the usual manner with drying-felts).

55 K K are the air-drums, and L L the steam-heated drying-cylinders, with the usual drying-felts, M. By this arrangement the paper may, if desired, be dried entirely by air, (the cylinders L being then used cold and serving merely to keep the paper flat and free from "cockles,") or may be dried partly by the air-drums and partly by the steam-heated cylinders.

60 By drying thus by the air-drums and steam-cylinders combined I greatly preserve the color and add to the brilliancy of the tints; but for some tints I find it better to use the cylinders cold. After the paper has passed through the drying apparatus it is reeled up in the ordinary manner, passing over the roll R to the reel-shaft T.

65 The felts M are used to simply press the paper against the cylinder L to absorb a portion of the moisture and keep the web of paper flat while the moisture is being expelled by the heat of the cylinder, said felts being made of thick woolen material. 80

70 The air-drums K are skeleton cylinders with wooden ribs across to support the paper web, and within said cylinders are arranged fans to blow air against the web of paper, and thus assist in drying the same, so as to avoid the necessity of applying great heat. 85

Having fully described my invention, what I desire to claim, and secure by Letters Patent, is—

75 1. In an apparatus of the class described, the combination, with a single pair of impregnating-rolls covered with an absorbent material, and means, such as described, for supplying the rolls with the mordant or dye, of a heated drying-cylinder, the endless felt M', 95 and the skeleton air-drums K, substantially as and for the purposes specified.

80 2. In an apparatus of the class described, the combination, with a single pair of mordanting-rolls covered with an absorbent material 100 and arranged side by side and operating to draw the web of paper between them in substantially a vertical direction, a single pair of dyeing-rolls, also covered with an absorbent material and operating on the paper web like the mordanting-rolls, and means for supplying 105 said rolls with a mordant and dye respectively, of a drying-cylinder arranged between the mordanting and dyeing rolls in a higher plane than either, substantially as and for the 110 purposes specified.

85 3. In an apparatus of the class described, the combination, with a single pair of mordanting-rolls covered with an absorbent material and arranged side by side and operating to 115 draw the web of paper between them in substantially a vertical direction, a single pair of dyeing-rolls, also covered with an absorbent material and operating on the paper web like the mordanting-rolls, and means for supplying 120 said rolls with a mordant and dye respectively, of a drying-cylinder arranged between the mordanting and dyeing rolls in a higher plane than either, and the endless felt M', 125 substantially as and for the purposes specified.

90 4. In an apparatus of the class described, the combination, with a single pair of mordanting-rolls covered with an absorbent material and arranged side by side and operating to 130 draw the web of paper between them in substantially a vertical direction, a single pair of

dyeing-rolls, also covered with an absorbent material and operating on the paper web like the mordanting-rolls, and means for supplying said rolls with a mordant and dye respectively, of a drying-cylinder arranged between the mordanting and dyeing rolls in a higher plane than either, the endless felt M', and the

series of air-drums K, substantially as and for the purposes specified.
